UNITED STATES PATENT OFFICE.

FRANCIS C. MASON, OF GRAND RAPIDS, MICHIGAN.

DESIGN FOR A DISPLAY-STAND.

SPECIFICATION forming part of Design No. 33,711, dated December 11, 1900.

Application filed November 6, 1900. Serial No. 35,679. Term of patent 14 years.

To all whom it may concern:

Be it known that I, FRANCIS C. MASON, a citizen of the United States, residing at the city of Grand Rapids, in the county of Kent and State of Michigan, have invented and produced a new and original Design for a Display-Stand, of which the following is a specification, reference being had to the accompanying drawings, forming a part thereof.

Figure 1 is a front elevation of a display-stand, showing my design. Fig. 2 is a side elevation showing the base-supports of the stand.

As shown in the drawings, the leading or material feature of my invention consists in a stand provided with two bases A A, each base secured to an upright standard B, the standards connected together by cross-braces, (shown by K K, &c.,) having at the top, between the upper cross-braces proper, the finishing-strip I and a plurality of turned rods,

leaving a space between the upper horizontal piece and the finishing top piece I, which space is filled with grillework formed by the turned rods, as shown in Fig. 1, and also having a cross-piece H.

In order to carry out more fully the principle of my invention, I provide a series of racks (shown by C C C) formed with a side projection E E.

Having thus described my invention, what I claim as new, and desire to secure by Letters Patent, is—

The design for a display-stand as shown and described.

In testimony whereof I have hereunto set my hand in presence of two subscribing witnesses.

FRANCIS C. MASON.

Witnesses:

EDWARD TAGGART,
JAMES B. DAVIES.
